UNITED STATES PATENT OFFICE

CHARLES LORBER, OF LOUISVILLE, KENTUCKY

KEY CASE

Application filed May 14, 1930. Serial No. 452,398.

This invention relates to key cases and has special reference to a key plate for such cases.

One important object of the invention is to provide a novel form of key plate angled to allow full room for the keys to lie flat against the body of the key case while, at the same time, effecting a very considerable economy of material over such key plates as have a tubular formation at their upper edge.

10 A second important object of the invention is to provide a novel form of key plate having a top flange projecting rearwardly of the plate to hold the case body away from the upper part of the plate so as to allow full room for the anchor base.

15 A third important object of the invention is to provide a plate of this class having anchor slots extending in both directions from the angle of the flange so as to lie partly in the flange and partly in the body of the plate and thereby permit positioning of the anchor so as to project either forwardly or rearwardly and thus allow full swinging and swivelling movement of the anchors, key 20 hooks and keys.

25 A fourth important object of the invention is to effect an easier and more economical assembling of the parts.

With the above and other objects in view, 30 as will be presently understood, the invention consists in general of certain novel features of construction and combinations of parts hereinafter fully described, illustrated in the accompanying drawing, and specifically claimed.

In the accompanying drawing like characters of reference indicate like parts in the several views, and:

Figure 1 is a perspective view of a key case 40 open and provided with the improved plate construction.

Figure 2 is a section on the line 2-2 of Figure 1.

Figure 3 is a section on the line 3-3 of 45 Figure 1.

Figure 4 is a modified section on the line 4-4 of Figure 1.

Figure 5 is a second modified section on the line 5-5 of Figure 1.

50 Figure 6 is a perspective view of the plate

shown in Figure 4, separate from the other parts.

The invention is here disclosed as applied to a key case of leather or other suitable material having a body 10 and cover flaps 11 folding on the body and secured in folded position by the snap button parts 12.

55 The key plate consists of a body portion 13 having in the form shown in Figures 1 to 3, a rearwardly and upwardly inclined flange 14, in Figure 4 a flange 15 extending rearwardly at right angles to the body and in Figure 5 a rearwardly and downwardly extending flange 16. In all the forms there are

60 anchor slots 17. Each anchor is made from round wire bent to provide an eye 18 and a shank 19 which extends through a respective slot to rotate therein and to slide from end to end thereof. After passing the anchors through their slots they are headed as at 19,

65 the operation being easily effected since the ends of the shank are fully accessible from the rear side of the plate. Key hooks 20 of the ordinary form have their upper ends engaged in said eyes. Thus the anchors may 70

75 project forwardly or upwardly as desired, the body of the case being held away from the heads 19 to allow free swinging and swivelling movement.

80 After assembly of the anchors, hooks and plate the latter is secured to the case body 10 by rivets 21.

85 There has thus been provided a simple and efficient device of the kind described and for the purpose specified.

It is obvious that minor changes may be 90 made in the form and construction of the invention without departing from the material spirit thereof. It is not, therefore, desired to confine the invention to the exact form herein shown and described, but it is desired to include all such as properly come within the scope claimed.

Having thus described the invention, what is claimed as new, is:

95 1. The combination with a key case having a body of flexible material; of a key plate having a flat body portion secured to the upper part of the case body, the lower part of said plate resting flat on said body, said 100

plate having slots for attachment of key hooks in its upper part, and a rearwardly extending flange on the upper part of the flat plate body lying wholly behind the body and having its rear edge engaging the case body and forcing the same rearwardly away from the slotted portion of the plate, and key hook eyes having shanks extending through said slots and provided with heads in the space between the body and plate, said shanks being slidable in said slots.

2. The combination with a key case having a body of flexible material; of a key plate having a flat body portion secured to the upper part of the case body, the lower part of said plate resting flat on said body, said plate having slots for attachment of key hooks in its upper part, and a rearwardly extending flange on the upper part of the flat plate body lying wholly behind the body and having its rear edge engaging the case body and forcing the same rearwardly away from the slotted portion of the plate, said flange being arranged at an obtuse angle to the plate body, and key hook eyes having shanks extending through said slots and provided with heads in the space between the body and plate, said shanks being slidable in said slots.

3. The combination with a key case having a body of flexible material; of a key plate having a flat body portion secured to the upper part of the case body, the lower part of said plate resting flat on said body, said plate having slots for attachment of key hooks in its upper part, and a rearwardly extending flange on the upper part of the flat plate body lying wholly behind the body and having its rear edge engaging the case body and forcing the same rearwardly away from the slotted portion of the plate, said slots extending into said flange and terminating in spaced relation to the rear edge of the flange, and key hook eyes having shanks extending through said slots and provided with heads in the space between the body and plate, said shanks being slidable in said slots to permit the eyes to project forwardly when in the portions of the slots below the flange and upwardly when in the portions of the slots in the flange.

4. The combination with a key case having a body of flexible material; of a key plate having a flat body portion secured to the upper part of the case body, the lower part of said plate resting flat on said body, said plate having slots for attachment of key hooks in its upper part, and a rearwardly extending flange on the upper part of the flat plate body lying wholly behind the body and having its rear edge engaging the case body and forcing the same rearwardly away from the slotted portion of the plate, said flange being arranged at an obtuse angle to the plate body, said slots extending into said flange and terminating in spaced relation to the rear edge of the flange, and key hook eyes having shanks

extending through said slots and provided with heads in the space between the body and plate, said shanks being slidable in said slots to permit the eyes to project forwardly when in the portions of the slots below the flange and upwardly when in the portions of the slots in the flange.

In testimony whereof I affix my signature.

CHARLES LORBER.
